(57) **CLAIM**

The ornamental design for a scaffolding modular node, as shown and described.

DESCRIPTION

The design is for a node used to connect scaffolding parts.

FIG. 1 is a top perspective view of a scaffolding modular node showing my new design;

FIG. 2 is a bottom perspective view of the scaffolding modular node.

FIG. 3 is a top plan view thereof, the bottom being identical thereto; and,

FIG. 4 is a side elevation view thereof, the opposite side being identical thereto.
